SAW HANDLE STRUCTURE

James N. Alexander, Birmingham, Ala.

Application December 18, 1933, Serial No. 703,020
Renewed February 26, 1935

4 Claims. (Cl. 145—35)

This invention relates to saw handles, and more particularly to saw handles of the ordinary handsaw type.

This application is a continuation in part and 5 an improvement upon my application Serial No. 681,633, filed July 21, 1933.

An object of my invention is to provide a light unitary metal structure in which the minimum of metal is used, and in which the lubricant 10 reservoir in the hand engaging portion not only provides for lubrication but also for decreasing weight.

Another feature of my invention is the provision of oiling means which will tend to prevent rusting of the blade in the place where the steel contacts with the metal of the handle.

Another important feature of my invention is to design a quickly detachable handle in which the means for holding the blade in place in the 20 handle will be protected from injury through chance blows.

I have illustrated in the accompanying drawing a detailed structure, which is only one embodiment. It is my desire that I be not limited to 25 the particular embodiments, but that I may be limited solely by the showing of the prior art and the scope of the appended claims.

In the drawing:

Figure 1 is a view in side elevation of my handle 30 attached to a saw blade.

Figure 2 is a view taken along the line 2—2 of Figure 1.

Figure 3 is a fragmentary sectional view showing a portion of the lubricating system.

Figure 4 is a view taken along the line 4—4 of Figure 1.

Figure 5 is a view taken along the line 5—5 of Figure 1.

Figure 6 is a view taken along the line 6—6 of Figure 2.

As the invention is described, other objects than those above set forth will become apparent.

Referring to the drawing, I have shown a metallic saw handle, which may be made of aluminum, which comprises a bifurcated blade engaging section 1 and a hand engaging portion 2. These two may be integrally formed from metal such as aluminum. The bifurcated blade engaging section 1 is provided with depressed areas 3, as is plainly seen from Figures 1, 2 and 4. These depressed areas have outer rims 4. Within the depressed areas are located apertures 5, through which fit the shanks 6 of wing bolts 7. The wing bolts 7 are provided with immovably attached 50 wing portions 8, with inwardly projecting lugs 9

that are adapted to fit within supplemental apertures 10 formed at the side of the main apertures 5. These lugs 9 engage the supplemental apertures 10 and tend to prevent rotation of the wing bolts 7 when seated in place.

There is a saw blade 11 which fits in a slot 12 formed in the bifurcated blade engaging section 1. It is understood that the saw blade 11 is provided with apertures corresponding to the apertures in the bifurcated section to receive the 10 wing bolts. The wing bolt shanks 6 are provided with portions of decreased diameter 13 which are screw threaded and over which fit revoluble wing portions 14.

This wing bolt assembly holds the saw blade 15 11 firmly in place. The assembly is light, by reason of the sunken or depressed areas so formed in the blade engaging section 1. It is to be particularly noted that the rims 4 surrounding the sunken areas 3 are of such height that the wing 20 bolts are completely shielded from contact with an object which will engage the rims 4. In other words, the bolts are sunk in the depressed areas 3 out of harm's way. This construction permits ready removal of the saw blades, quick adjustment manually to tighten the saw blades in case they work loose while in the field, and at the same time the holding means for the saw blade is not apt to be injured by chance blows, because of the excellent protection afforded by the rim. 30 It is to be noted that the wing bolts will not rotate once the lugs 9 are in the apertures 10.

The saw handle is further lightened by two oil reservoirs 15, which are located in the handle. These oil reservoirs are separated by a dividing 35 partition 16 and constitute separate oil systems. Each oil reservoir 15 communicates with a passageway 17, which at its outer end has a fixture 18 that is screw threaded into the metal of the blade engaging section. These elements 18 have a hollow central portion 19 (see Figure 5), and a tapered nozzle 21 provided with a central oil aperture 22.

These elements 19 are provided with pressure flip valves 23 which prevent passage of the oil 45 from the reservoirs 15 until they are subjected to pressure. These flip valves 23 are rubber valves. Their configuration is shown in cross section in Figure 5. Each rubber flip valve is of nipple shape, the tip of the nipple being split, as indicated at 24. The rubber material gives at the teat, the split opens when the pressure of the oil in the reservoir is high enough to distort the rubber at the teat. The rubber is ordinarily sufficiently resistant to withstand the weight of the 50 55

column of liquid in each reservoir 15 without permitting the split in the teat to open. Such valves are true pressure valves, and are of very simple construction. It is to be noted that these flip valves 5 are protected from harm by reason of the construction of the elements 18 and are not subjected to injury through blows.

Each reservoir 15 is provided with an open section 25 over which fits a flexible cover 26. Each 10 reservoir is fillable through an aperture 27, closed by a knurled plug 28.

In use, the operator of the saw will squeeze upon either of the covers 26 of either of the reservoirs 15 to eject a stream of oil through the flip valves 15 and onto the working surface of the saw.

It is to be noted that the reservoirs and oil systems are separate. This is a feature of importance, since one face only of the blade should be oiled at one time. The saw blade, when being 20 oiled, is placed approximately parallel to the ground, and the upper face has oil ejected upon it in order to lubricate it. If the undersurface of the blade had oil ejected upon it at this time, the stream of oil would mostly dribble upon the 25 ground, and the operation would be quite inefficient.

The location of the reservoir in the handle permits the blade adjacent the bifurcated blade engaging section to be lubricated, thereby preventing 30 rusting of the blade in place within the metallic handle. This feature is of considerable utility because there is more danger of adherence of the blade to the handle where metal contacts metal than would be the case where a blade was 35 inserted in a wooden saw handle. The oil can be ejected without much force, and will tend to lubricate the contact areas between the blade and the bifurcated parts of the blade engaging section 1. The reservoir in the handle, together 40 with the sunken areas 3, lighten the construction so that when the saw handle is made of a light metal such as aluminum it is not unduly heavy or cumbersome.

I claim:

45 1. A metallic saw handle of integral construction comprising a bifurcated blade engaging section integrally formed from the metal of the handle, a hand engaging portion formed integrally with the bifurcated blade engaging section, a 50 divided lubricant reservoir within the handle, the dividing wall thereof operating as a structural brace behind the bifurcated blade engaging sections, means at the forward edge of the handle and in communication with the reservoir to direct 55 the lubricant upon the working area of the blade, spray means operating on each side of the

divided parts of the reservoir for controlling the ejection of the lubricant on one face only of the blade, the blade engaging section being provided with sunken areas and means to hold the blade in the section, and wing bolts in said areas to hold the blade of the saw, the depth of the sunken areas being such as to completely submerge the wing bolts below the level of the metal around the edge of the depression. 5

2. A metallic saw handle comprising a bifurcated 10 blade engaging section integrally formed with the metal of the handle, a hand engaging portion formed integrally from the bifurcated blade engaging section, two lubricant containers within the hand engaging portion, means in communication with each container to direct the lubricant therefrom onto one working surface only of the blade, other means in line with the center of the bifurcated blade engaging section normally to prevent communication between 20 each lubricant container and said last mentioned means, the blade engaging section being provided with sunken areas, and wing bolts in said areas to hold the blade of the saw, the depth of the sunken areas being such as to completely sub- 25 merge the wing bolts below the level of the metal around the edge of the depression.

3. A metallic saw handle of integral construction comprising a handle grip having openings in each side thereof with reservoir chambers 30 formed below the openings, flexible means to close the openings, means operable through the flexible means to oil the saw, a central brace acting as a dividing partition for the reservoir integrally formed with the handle grip, a bifurcated 35 blade engaging extension forward of the handle and having a median saw engaging slot in line with the central brace of the handle grip, and means to hold the saw blade in the extension. 40

4. A metallic saw handle of integral construction comprising a handle grip having openings in each side thereof with reservoir chambers formed below the openings, flexible means to close the openings, means operable through the flexible 45 means to oil the saw, a central brace acting as a dividing partition for the reservoir integrally formed with the handle grip, a bifurcated blade engaging extension forward of the handle and having a median saw engaging slot in line with the central brace of the handle grip, said extension having a sunken area and means to hold the blade in the extension which shall lie wholly below the edge of the sunken area. 50
